[57] **CLAIM**

The ornamental design for a magnetic disc drive with coupling member for a word processor, shown and described.

DESCRIPTION

FIG. 1 is a top, front, right side perspective view of a magnetic disc drive with coupling member for a word processor showing our new design;

FIG. 2 is a top plan view thereto on an enlarged scale;

FIG. 3 is a bottom plan view thereof on an enlarged scale;

FIG. 4 is a front elevational view thereof on an enlarged scale;

FIG. 5 is a rear elevational view thereof on an enlarged scale;

FIG. 6 is a right side elevational view thereof on an enlarged scale; and

FIG. 7 is a left side elevational view thereof on an enlarged scale.
